DUPLICATING MECHANISM

John W. Hernlund, La Grange, Cecil C. McCain,
 Glen Ellyn, and Alfred Marchev, La Grange,
 Ill., assignors to Ditto, Incorporated, a corpo-
 ration of West Virginia

Application October 30, 1933, Serial No. 695,920

15 Claims. (Cl. 101—132)

This invention relates to duplicating machines of the rotary type and more especially, though not exclusively as to all of its features, to duplicating machines employing a master sheet presenting in reverse, or negative, condition thereon the transfer-ink impression of which copies are to be made on sheets of paper fed to the machine, produced, as for example, by typing the sheet which is to form the master sheet, against a transfer-ink carbon sheet applied to the back thereof, the sheets from which the duplicates are to be made being moistened, preliminary to the making of the impressions thereon, with a solvent of the ink from which the impression on the master sheet is made.

Certain of the objects of the invention are to provide for the more rapid printing of the sheets; to provide for the automatic clamping of the master sheet to the impression cylinder of the machine as the first step in the operation of conditioning the machine for the making of copies of the impression; to provide for the release of the master sheet from the impression cylinder, under the control of the operator, by the continuation of the operation of the driving means in the same direction as when producing the copies; to provide for the accurate alignment with the master sheet of the sheets to be printed and particularly useful where rule-line registration is necessary; to provide against the rotation of the impression cylinder in case of failure to present a sheet at the proper time to the means for feeding the sheets into cooperative relationship with the impression cylinder; and other objects as will be manifest from the following description.

Referring to the accompanying drawings:

Figure 1 is a view in side elevation of a machine embodying our invention.

Figure 2 is a plan view of the machine.

Figure 3 is a section taken at the line 3—3 on Fig. 2 and viewed in the direction of the arrows.

Figure 4 is an enlarged sectional fragmentary view showing that portion of the impression cylinder which is equipped with clamping means for the master sheet showing these clamping means in open position and illustrating the master sheet as fed into a position to be engaged by these clamping means.

Figure 5 is a similar view of the parts shown in Fig. 4 illustrating the clamping of the master sheet in the movement of the cylinder out of the position shown in Fig. 4.

Figure 6 is a similar view of the parts shown

in Figs. 4 and 5 showing the machine upon the completion of one revolution of the cylinder from the position shown in Fig. 4 and illustrating the position to which the sheet upon which the impression is to be made is fed upon the cylinder reaching this position.

Figure 7 is a broken plan sectional view taken at the line 7 on Fig. 8 and viewed in the direction of the arrow.

Figure 8 is a section taken at the line 8—8 on Fig. 3 and viewed in the direction of the arrows.

Figure 9 is a plan sectional view taken at the irregular line 9—9 on Fig. 8 and viewed in the direction of the arrows.

Figure 10 is a broken fragmentary sectional view taken at the irregular line 10—10 on Fig. 8 and viewed in the direction of the arrows.

Figure 13 is a section taken at the line 13—13 on Fig. 11 and viewed in the direction of the arrows.

Figure 14 is a broken section taken at the irregular line 14—14 on Fig. 11 and viewed in the direction of the arrows.

Figure 15 is an enlarged fragmentary section taken at the line 15—15 on Fig. 14 and viewed in the direction of the arrows.

Figure 16 is a fragmentary section taken at the irregular line 16—16 on Fig. 11 and viewed in the direction of the arrows.

Figure 17 is an enlarged fragmentary section taken at the irregular line 17—17 on Fig. 2 and viewed in the direction of the arrows this view illustrating the positions occupied by the parts of the machine when the machine is at rest following one complete cycle of operation.

Figure 18 is a similar view, showing the impression drum at the beginning of its cycle of revolution showing the position of the cylinder-driving means provided a sheet has been introduced into the machine into a position for feeding.

Figure 19 is a view like Fig. 17 illustrating a position of the parts of the cylinder and its driving means and the control means therefor in the event that no sheet has been introduced into the sheet-feeding means.

Figure 20 is a fragmentary section taken at the line 20—20 on Fig. 11 and viewed in the direction of the arrows.

Figure 21 is a fragmentary section taken at the line 21—21 on Fig. 19 and viewed in the direction of the arrows and illustrating certain controlling means for the feed rolls.

5 Figure 22 is a similar view of the same part showing another position occupied thereby.

Figure 23 is a fragmentary plan section taken at the line 23 on Fig. 19 and viewed in the direction of the arrow.

10 Figure 24 is a fragmentary section taken at the line 24—24 on Fig. 23 and viewed in the direction of the arrows.

Figure 25 is a perspective view of a bed plate of the machine over which the sheets are fed to 15 the duplicating cylinder.

Figure 26 is a perspective view of a margin bar forming a part of the machine.

Figure 27 is a perspective view of a feeler device constituting a part of the mechanism controlling 20 the operation of the machine in the event of failure of delivery of a sheet to the feed means; and

Figure 28, a perspective view of the upper one of the feed rolls and the mounting therefor.

Referring to the particular illustrated embodiment of the invention, it comprises a frame presenting side plates 30 and 31 rigidly secured together in spaced apart relation by shouldered tie rods 32, 33 and 34.

30 At one end of the frame and extending into the space between the side plates is a bed plate structure shown as comprising two sections 35 and 36 (Fig. 3) and forming a support along which the master sheet and the copy sheets are fed to the mechanisms hereinafter described. At 35 the opposite end of the frame and extending into the space referred to is an inclined delivery chute 37 shown as supported on the tie rod 34 in a position below the bed plate structure and to which the master sheet, after the printing operations 40 are completed, and the printed copy sheets, are delivered.

45 The impression cylinder represented at 38 (Fig. 3) and located adjacent the inner end of the bed plate structure 35—36 and directly above the receiving end of the chute 37 is shown as comprising end disks 39 and 40 (Fig. 11) and a cylindrical side-wall-forming portion 41 rigidly secured together, the cylinder being rotatably mounted at its ends on stub shafts 42 and 43 stationarily secured to the frame-sides and forming journals for the cylinder.

50 The cylinder 38 is adapted to carry a master sheet, such as that represented at 44 (Fig. 3), wrapped about it and presenting on its outer exposed face the transfer-ink impression in reverse, or negative, condition as above referred to, whereby positive, as distinguished from negative, impressions are made on the moistened sheets successively presented to the master sheet as hereinafter described.

55 The means for securing the master sheet 44 to the cylinder 38 comprises a clamp bar 45 located in a recess 46 in the outer face of the cylinder 38 and extending lengthwise thereof and secured at 60 ears 47 on a shaft 48 located in the recess 46 and journaled in the end walls thereof. The clamp bar 45 is of slightly less length than the length of the cylinder 38 and is provided with a bevel surface 49 between which and a corresponding bevel surface 50 on the cylinder 38 at the mouth of the slot 46 the upper edge of the master sheet 44 is clamped, the outer face of the clamp bar 45 being convexed as represented at 51 (Fig. 5).

70 One end of the shaft 48 (Fig. 13), carries an arm 52 the outer end of which is pivoted at 75

to one end of a rod 54 slidable in a stud 55 projecting from the end disk 39 of the cylinder 38, the arm 52 and rod 54 forming a toggle having a coiled compression spring 56 between the toggle joint and the lug 55 which is placed under compression in the movement of the toggle toward dead center position and thus operates to snap the toggle in passing over dead center when actuated as hereinafter described, the pivot 53 being provided at its outer end, beyond the spring 10 56 and lug 55 with a roller 57 for a purpose hereinafter described.

The mechanism for rotating the cylinder 38 (Figs. 1, 11 and 19) comprises a crank 58 journalled on the side frame 30 and carrying a pinion 15 59 which meshes with a gear 60 surrounding, and secured to, a sleeve 61 journaled on the stub shaft 43, the gear 60 being connected, as by screws one of which is represented at 62, to a cam ring 63 and a clutch ring 64 surrounding the sleeve 61 20 and shown as formed integrally with a connecting sleeve portion 65, the cam ring 63 being shown as provided about its periphery with three similarly shaped and equidistantly spaced cams 66, 67 and 68.

25 The ring 64 which forms a portion of clutch mechanism through the medium of which the cylinder 38 is rotated by the gear 60 is provided in its periphery with three semi-circular equidistantly spaced recesses 69, 70 and 71, (Figs. 17 and 20), and is surrounded concentrically, but in spaced relation thereto, to provide the annular space 72, by a ring 73 stationarily secured to bosses 74 extending inwardly from the side frame 30, the inner periphery of the ring 73 containing 35 a notch represented at 75.

The clutch mechanism now being described also comprises a roller 76 interposed between the rings 64 and 73 and of such diameter as shown that when it is entered in the recess 75 it does not obstruct free rotation of the ring 64, as shown 40 in Figs. 17 and 19, but when entered in any one of the recesses 69—71 it will be held against displacement therein by the inner periphery of the ring 73, as shown in Fig. 20 thereby clutching the cylinder 38 to the ring 64 for rotation therewith. The roller 76 (Figs. 11 and 12) is carried on the outer end of a pin 77 secured to one end of a bell-crank lever 78 located in a recess 79 in the outer face of the end disk 40 of the cylinder 38 and fulcrumed thereon as represented at 80, the other arm of this bell-crank being connected with one end of a coiled spring 81 the other end of which is connected with the cylinder end, whereby the spring tends to rock the bell-crank 78 at all times in a direction outwardly from the center of the cylinder and into the recess 75 when in registration therewith to unclutch the cylinder from the driving means except when restrained by mechanism hereinafter described.

60 Located below the cylinder 38 (Fig. 19) is a presser roller 82 preferably of rubber provided, in the particular machine shown, for a double purpose, one of which is to actuate the master-sheet-clamping bar 45 from the open position 65 shown in Fig. 4 to the closed position shown in Figs. 3 and 5 by the rolling of the surface 51 of the clamp against this roller in the rotation of the cylinder 38 during the application of the master sheet thereto, as shown in Fig. 5; and the other 70 of which is to press the impression on the master sheet 44 against the sheets of paper on which the duplicate impressions are to be produced. The roll 82 (Figs. 3, 8, 19) which is located between the bed plate structure, 35, 36 and the chute 37, 75

is journaled at its ends 83 in blocks 83^a slidably mounted in upwardly extending yokes 84 on the ends of a bar 85 straddled by the sides 86 of a yoke block 87 to which the bar 85 is pivotally connected midway between its ends to permit it to rock lengthwise, by a pivot pin 88, the bar 85 being guided at its ends by centering pins 85^a secured to the frame-sides 30 and 31 and extending into the yokes 84. The block 87 is mounted at a circular opening 89 therein on an eccentric 90 rigidly secured to a shaft 91 journaled in the frame sides 30 and 31, the roller 82 thus being adjustable relative to the cylinder 38 to adapt the machine for operating with master sheets and copying sheets of different thicknesses, the supporting of the roller 82 on the pivot 88 insuring the application of uniform pressure by the roll 82 throughout its length.

For convenience of rotary adjustment of the shaft 91 it is provided with a crank handle 92, the shaft being held in any of the positions of adjustment thereof by means of a gear 93 (Fig. 10) rigid on the shaft 91 and cooperating with a spring pressed plunger 94 mounted on the frame.

Referring now to the mechanism by which the master sheet and thereafter the copy sheets are fed to the cylinder 38 and the transfer-ink solvent applied thereto, this mechanism comprises a pair of parallel rollers 95 and 96 (Figs. 1, 9, and 17) extending crosswise of the machine in front of the cylinder 38, the roller 95, preferably felt covered, extending upwardly into a slot 97 in the bed plate section 36 and journaled at its ends in the frame sides 30 and 31, this roller having a pinion 98 connected through the medium of gears 99 and 100 with the gear 60.

The roller 96 which is preferably of rubber is geared to the roller 95 to rotate at all times therewith, but in the opposite direction, through the medium of intermeshing gears 101 and 102 (Fig. 8) on the rollers 96 and 95, respectively, the roller 96 being journaled at its ends in a rock frame represented generally at 103 (Fig. 28) formed of end members 104 connected together by a longitudinally extending member 105 from which frame a finger 106, provided for a purpose hereinafter described, forwardly projects. The frame 103 is journaled on the stationary frame of the machine by means of stub shafts 107 projecting inwardly from the frame sides into bosses 108 on the frame 103.

The frame 103, which is adapted to be swung with its roller 96 toward and away from the roller 95 as shown in Figs. 17 and 19 to permit of the entry between these rollers of a sheet to be fed thereby, is connected at a part 109 with the lower end of a coiled spring 110 the other end of which is connected with the frame of the machine, this spring tending to constantly urge the roller 96 toward the roller 95. A roller 111 on the frame 103 cooperates with mechanism hereinafter described and operated by the cam-equipped rings 63 to control the position of the roller 96 relative to the roller 95, it being understood that when the spring 110 is free to act as shown in Figs. 18 and 19, the roller 96 will be pressed toward the roll 95 with sufficient force to exert feeding action on a sheet interposed between these rollers.

The mechanism now being described also comprises means for supplying the liquid solvent for the transfer-ink to the peripheral surface of the roller 96 the means shown for this purpose comprising a reservoir 112 (Fig. 18) for the solvent mounted on the frame of the machine to extend

crosswise thereof, and a trough 113 below the reservoir 112 and supplied with the solvent through an outlet pipe 114 opening into the top of the trough 113, the trough 113 containing a wick 115 depending into the liquid in the trough with its upper edge portion bearing against the periphery of the roller 96, the solvent thus being carried to the outer edge of the wick and thence to the roller 96 by capillary attraction.

The wick 115 is held in place by a plate 116 the pressure of which against the wick, and which pressure thereby determines the amount of feed of solvent to the roller 96, is controlled by a pressure-applying nut 117 screwed upon the upper end of a stud 118 rising from the trough.

The trough 113 is preferably pivotally mounted on an axis disposed crosswise of the machine as by the means of stub shafts 119 (Fig. 1) at the ends of the trough journaled in stationary lugs 120 beyond the trough-ends. A coil spring 121 pressing upwardly against a lug 122 on the front of the trough serves to exert the desired pressure of the wick 115 against the roller 96.

The means for controlling the feeding of solvent from the reservoir 112 to the trough 113 for maintaining a constant level of the solvent in the trough is of the well known type involving the maintaining of the reservoir 112 closed to the atmosphere except through a passage the opening and closing of which is controlled by the level of the solvent in the trough 113. To render smooth and accurate the feed of the solvent to the trough 113, a supplementary, air, pipe 123 shown as of considerably larger diameter than the pipe 114 opens into the upper end of the reservoir 112 and into the trough 113 substantially at the level of the lower end of the pipe 114. Thus when the level of the solvent in the trough 113 drops below the lower ends of the pipes 114 and 123, atmospheric air enters the lower end of pipe 123 for passage into the reservoir permitting of the flow of solvent therefrom to the trough to an amount sufficient to reestablish equilibrium, whereupon the flow ceases.

The machine also comprises a margin bar 124 which is movable up and down into and out of the path of movement of sheets manually introduced into the space between the rollers 95 and 96 when the latter are separated, to insure the proper positioning of the sheet upon the starting of the feed thereof by these rollers. This margin bar, represented at 124 (Fig. 26), is shown as of sheet material with a rearwardly and upwardly curved edge terminating in a series of stops 125 extending crosswise of the machine and rearwardly beyond the centers of the rollers 95 and 96, the bar 124 being journaled at its ends on stationary stub shafts 126 to rock in a vertical plane. A coil spring 127 secured to the bar 124 to the rear of its pivot and to the frame of the machine tends to rock this bar into the raised position shown in Fig. 17.

The stop portions 125 register with openings 128 in the rear edge portion of the bed plate section 36 (Fig. 25) adapting these stop portions to extend upwardly through the openings 128 when the margin bar 124 is in the raised position shown in Fig. 17 wherein it is in position to properly position the sheet inserted into the machine. As shown more particularly in Fig. 26 the edge portion of the margin bar on which the stop portions 125 are provided is cut away at its ends as represented at 129 thereby affording the offset lower surfaces 130 for the purpose hereinafter described.

The finger 106 of the roller frame 103 extends within the notch at one end of the margin bar 124 and laps the upper surface of the latter, for controlling the position of the margin bar relative to the bed plate 35, 36. These parts are so arranged, as shown, that in the movement of the roller 96 toward the roller 95 by the swinging of the frame 103, the margin bar is forced downward against the action of the spring 127 to the lowered position shown in Fig. 18 in which the sheet stops 125 extend out of the path of movement of the sheet between the rollers 95 and 96 to permit the latter to feed the sheet; and in the movement of the roller 96 away from the roller 95 the margin bar swings upwardly, under the action of its spring 127 (Fig. 17) to project the stop portions 125 into the path of movement of the next sheet inserted into the machine.

The clutching of the cylinder 38 to the drive mechanism above described and the actuation of the roller frame 103 and margin bar 124 is effected by means of a lever 130 fulcrumed between its ends to the stationary ring 73, as indicated at 131. The lower end of the lever 130 which is connected with a coil spring 132 tending to rock this lever clockwise to the position shown in Fig. 18, is adapted to engage the roller 111 on the roller frame 103 and rock the latter clockwise to the position shown in Fig. 17 when this lever is rocked counter-clockwise in this figure.

The rocking of the lever 130 is controlled by the cams on ring 63 into the path of movement of which a roller 133 on the upper end of the lever 130, extends.

The lever 130 is provided at its upper end with an angularly disposed finger 134 which, when this lever is swung to the position shown in Fig. 18, forces the clutch pin 76 into one of the peripheral recesses in the ring 64 thus establishing driving connection between this drive ring and the cylinder 38 whereby these parts rotate together.

Assuming the machine to be at rest and the various parts to be in the positions shown in Fig. 17 in which position the clutch roller 76 extends into the recess 75 in the stationary ring 73 and thus out of cylinder-driving position, and the roller 96 and margin bar 124 are in raised position, the operator introduces into the space between the rollers 95 and 96 and against the margin bar 124, the master sheet 44 to be applied to the cylinder 38 and from which the impressions are to be made on the copy sheets, with the transfer-ink impression, in reverse on the master sheet, facing downwardly. The crank 58 is then turned clockwise in Fig. 17 rotating the cam ring 63 and clutch ring 64 counterclockwise.

In the movement of the receding portion of the cam 66 across the roller 133 the lever 130 is rocked clockwise by the spring 132 which permits the roller frame 103 to be rocked counterclockwise by the spring 110 thus moving the roller 96 downward against the master sheet, to establish drive connection between the rollers 95 and 96 and the sheet, and depressing the margin bar 124 to permit of the feeding of the sheet by these rollers.

At the end of this rocking movement of the lever 130 the finger 134 engages the clutch pin 76 forcing it against the action of the spring 81 into the recess 69 in the drive ring 64 thus starting the drive of the cylinder 38.

The parts described are proportioned and arranged as shown that the master sheet 44 will be fed by the rollers 95 and 96, which move at the same surface speed as the cylinder 38, to a posi-

tion in which its rear edge portion extends into the recess 46 in the cylinder between the surface 47 and the clamp bar 45 which in this operation of the machine is open (Fig. 4), the rollers 95 and 96 continuing to feed the sheet at the same speed as the surface speed of the cylinder 38 so that when the clamp bar 45 moves against the roller 82, thus causing the bar 45 to spring to clamping position (Fig. 5), the master sheet becomes clamped to the cylinder. It may be here stated that in the particular construction shown the crank is so geared to the drive ring 64 that it requires three revolutions of the crank for one complete revolution of the cylinder 38.

The operator continues to rotate the crank 15 to wind the master sheet about the cylinder and when the cam 66 again engages the roller 133, namely, toward the end of the complete rotation of the cylinder which raises the roller 96 and the margin bar 124 (Fig. 17), he inserts a sheet 20 to be printed and represented at 135 beneath the roller 96 and against the stop portions 125 of the margin bar. As the roller 133 rides down the cam 66 in the continued rotation of the crank the lever 130 rocks clockwise to permit the roller 25 96 to press the sheet 135 against the roller 95 and lower the margin bar 124, the finger 134 moving downwardly to the position shown in Fig. 18 for maintaining drive connection between the clutch roller 76 and the rotating ring 64. 30

The timing of the operation of the rollers 95 and 96 on the sheet 135, relative to the rotation of the cylinder 38 is such, as explained in connection with the delivery of the master sheet to the cylinder, that the rear edge of the sheet 135 35 becomes registered with the clamped edge of the master sheet 44 as represented in Fig. 6, so that the impression produced on the copy sheet, as hereinafter described, will occupy the same position thereon as it does on the master sheet. These 40 sheets continue to move at the same speed, the sheet 135 flatwise opposing the underside of the master sheet and entering between the master sheet and the roller 82 as shown in Fig. 3 and the surface coming in contact with the master sheet 45 having first been moistened by the moistening means above described insures the receiving of an impression from the master sheet, the printed sheet, in the continued rotation of the cylinder dropping into the chute 37 with its impression surface uppermost. The cycle of operations just described is repeated for each successive sheet to be printed from the master sheet. 50

The machine also comprises means whereby the master sheet may be removed from the cylinder 55 by a semi-automatic operation and without requiring reversal of the cylinder. The means shown for this purpose comprise a plunger rod 136 provided at its lower end with a block 137, 60 slideable vertically in a channel 138 in a guide member 139 secured to the frame side 31 (Figs. 3, 11, 14, 15). The rod 136 extends upwardly above the frame side to expose it for operation and is yieldingly held in the raised position shown in these figures by a coil spring 140 interposed between a stop 141 on the rod 136 and a washer 142 surrounding the rod and bearing against the guide member 139. A cross pin 143 in the guide member and extending through a vertically elongated slot 144 in the block 137 limits the vertical movement of this block in both directions. 65

The block 137 is provided with an upward extension 145 having a terminal portion 146 which extends beyond the face of the block as shown in Fig. 15 and is of triangular shape (Fig. 14).

presenting an inclined face 147. The portion 147 of the block 137 extends in the vertical plane in which the roller 57 (Fig. 13) bodily moves in the rotation of the cylinder 38, but in the normal raised position shown in the drawings is out of the path of this roller, the inclined face 147 of the projection permitting the roller to move without obstruction. When the operator forces the rod 136 downwardly the portion 147 of the block 10 137 extends into the path of movement of the roller 57 for moving the clamp-bar toggle to the open position shown in Fig. 4, and thereby releasing the master sheet 44 which, in the continued rotation of the cylinder, discharges into the chute 15 37.

10 A roller equipped pin 148 secured to the frame side 31 and which is out of the path of the roller 57 when the clamp 45 is in clamping position and the cylinder is rotating, is so positioned that 20 it will be engaged by the roller 57 assuming the clamp has been opened (Fig. 4) and the cylinder 38 is rotated in a reverse direction by accident or otherwise, thus automatically actuating the clamp mechanism to closed position in which the 25 clamp may move against the roller 83 without gouging it and which would otherwise be the case were this clamp bar to move in open position (Fig. 4) against this roller in the rotation of the cylinder clockwise.

30 The machine also comprises means, referred to herein as feeler means, which operate automatically to control the driving of the cylinder 38, whereby should the operator fail to insert a sheet into the machine between the feed rollers 95 and 35 96 at the proper time, the drive means will be disconnected from the cylinder and the latter will remain stationary, in the continued operation of the drive means, until the operator resumes the insertion of the sheets into the machine, a sheet, however, being insertable upon the succeeding 40 turn of the crank thereby eliminating the necessity of making three turns of the crank, these means also serving to prevent the insertion of sheets into the machine while the roller 96 and 45 margin bar 124 are in lowered position.

The means shown for this purpose comprise a rock frame 149 (Fig. 27) formed of end members 150 and 151, a cross bar 152 connecting these members together at one side of the frame, and 50 an upwardly extending lug 153 on the cross bar 152, the outer end of the member 150 being notched as represented at 154 and the outer end of the member 151 having a projection 155.

The frame 152 is pivoted at openings 156 in 55 its end members 150 and 151 on the shaft of the roller 95, with its lug 153 in registration with a slot 157 in the bed plate section 36. A coil spring 158 connected with the projection 155 and with the frame of the machine tends to rock the frame 60 149 into a position in which its lug 153 extends upwardly through the slot 157 (Fig. 19) traversed by the sheet in inserting it into the machine.

The outer ends of the members 150 and 151 65 overlie the surfaces 130 of the margin bar 124 and the parts are so arranged as shown that when the margin bar is moved to lowered position (Fig. 19) the frame 149 may swing therewith, under the action of the spring 158, to the raised position shown in this figure if no sheet has been inserted into the machine, in which position the lug 153 extends upwardly through a slot 201 in a stationary plate 200 located directly above, and 70 spaced from, the bed plate structure 35, 36, but when the margin bar 124 is swung upwardly to the

position shown in Fig. 17 it rocks the frame 149 to the lowered position shown in this figure.

In the raised position of the frame 149 (Fig. 19) the notch 154 extends into the path of movement of a stud 159 on the lower end of the lever 130 and shown as of triangular shape in cross section, and prevents the swinging of this lever to a position in which the finger 134 thereon would force the clutch roller 76 out of the recess 75 in the stationary ring 73 in which position of the clutch 10 roller the cylinder is unclutched from the drive means.

It will thus be understood that so long as sheets are inserted in succession into the machine at the proper timed intervals during the operation 15 of the machine, three crank turns only would be necessary for each printed copy because each succeeding sheet would be so timed as to be between the lug 153 and the upper plate 200 which would prevent the frame 149 from rocking into a position to obstruct free movement of the lever 130. Should the operator fail to insert a sheet into the machine at the proper time the frame 149 swings upwardly effecting the stopping of the cylinder 38 as above stated. However, the cams on the 25 ring 63 continue to act in succession against the lever 130 but without shifting the clutch roller 76 to cylinder-driving position because there is no sheet to obstruct the upward movement of the 30 feeler frame.

When the proper manual feed of the sheets to the machine is resumed, the lever 130 is free to force the clutch roller 76 into cylinder-driving position when actuated by the spring 132 on lower end of same, as the roller 133 recedes from the 35 adjacent one of the cams on ring 63, as shown on Fig. 18.

The provision of the three cams 66, 67 and 68 is desirable as thereby it is unnecessary, in starting the machine into operation, to rotate the 40 crank handle more than one revolution after the operator resumes the inserting of the sheets into the machine.

It is desirable that the roller 96 remain in contact with the top surface of each sheet inserted therein throughout its travel in order that the solvent may be uniformly transferred over its entire top surface. To accomplish this means are provided whereby the roller 133, following the operation of the lever 130 which conditions 50 the clutch roller 76 for the beginning of the cycle of operation of the cylinder 38, is automatically shifted out of the path of the two succeeding cams on the ring 63 represented by 67 and 68 (Fig. 19) and thereafter is automatically returned to cam-engaging position. These means involve the mounting of the roller 133 on a pin 160 slidable on the lever 130 crosswise thereof (Figs. 21, 22) and normally pressed by a coil spring 161 into a position in which it is out of the path of movement of the cams 67, 68 (Fig. 21), the roller-equipped pin 160 cooperating at its outer end 162 with a stationary arcuate cam 163 secured to the end member 40 of the cylinder 38. The cam 163 is so shaped and positioned on the cylinder that the pin 160 will be in engagement with the cam 163, causing the roller 133 to occupy the position shown in Fig. 22, at the beginning of the cycle of operation of the cylinder 38, the spring 161 forcing the pin 160 to the position shown in Fig. 21 70 to clear the next two succeeding cams on the ring 63.

The journal 42 for the cylinder 38 which is rotatable in the frame side 31 and is slidable endwise from the cylinder, is held in place by a

screw 164 screwing into the frame side and bearing at its head 165 against a flange 166 on the journal, the flange, to permit of quick release of the journal, containing an arcuate peripheral recess 167 which, when the screw 164 is loosened and the journal rotated to cause this recess to register with the screw-head, permits of the withdrawal of the journal.

While we have illustrated and described a particular embodiment of our invention we do not wish to be understood as intending to limit it thereto as the same may be variously modified and altered and the invention embodied in other forms of structure without departing from the spirit of the invention.

What we claim as new, and desire to secure by Letters Patent, is:

1. In a machine of the character described, a rotatable impression cylinder, means for driving said cylinder, means for feeding sheets to said cylinder, means operating in timed relation to said cylinder for rendering said sheet-feeding means functionally inoperative, stop means movable into and out of a position for preventing the entry of sheets into said sheet-feeding means and means whereby said stop means extend in sheet-obstructing position in the operative condition of said sheet-feeding means.

2. In a machine of the character described, a rotatable impression cylinder, means for driving said cylinder, means for feeding sheets to said cylinder comprising cooperating rollers to receive the sheet, said rollers being separable to permit the sheets to be introduced between them, means operating in timed relation to said cylinder for separating said rollers, stop means movable into and out of a position for preventing the entry of sheets into said sheet-feeding means, and means whereby said stop means extend in sheet-obstructing position in the operative condition of said sheet-feeding means.

3. In a machine of the character described, a rotatable impression cylinder drive means, a releasable clutch connecting said cylinder with said drive means and releasable at one point only in the rotation of said cylinder through one printing cycle, means urging said clutch to released position, means for feeding sheets to said cylinder operating in timed relation to said cylinder, and means controlled by the sheets delivered to the machine operating, upon the regular delivery of the sheets to the machine, to maintain said clutch in driving condition against the resistance of said second-named means.

4. In a machine of the character described, a rotatable impression cylinder, drive means, a releasable clutch connecting said cylinder with said drive means and releasable at one point only in the rotation of said cylinder through one printing cycle, means urging said clutch to released position, means for feeding sheets to said cylinder operating in timed relation to said cylinder, a rock lever operable to maintain said clutch in driving condition against the resistance of said second-named means, and a device controlled by the delivery of sheets to the machine for controlling the operation of said lever operating to render said lever inoperative to actuate said clutch against the resistance of said second-named means upon failure of regular delivery of the sheets to the machine.

5. In a machine of the character described, a rotatable impression cylinder, drive means, a releasable clutch connecting said cylinder with said drive means and comprising a stationary

ring containing a recess on its inner periphery, a rotatable ring driven by said drive means and located within said first-named ring and having a recess in its outer periphery and a clutch element on said cylinder located between said rings said element when positioned in said first-named recess being out of driving engagement with said rotatable ring and when positioned in the recess in said rotatable ring and opposing the unrecessed portion of said first-named ring operating to drive said cylinder, means for feeding sheets to said cylinder operating in timed relation to said cylinder, and means controlling said clutch and controlled by the sheets delivered to the machine whereby said clutch element is caused to enter the recess in said first-named ring to release said clutch upon failure of delivery of a sheet to the machine.

6. In a machine of the character described, a rotatable impression cylinder, drive means, a releasable clutch connecting said cylinder with said drive means and releasable at one point only in the rotation of said cylinder through one printing cycle, means for feeding sheets to said cylinder operating in timed relation to said cylinder, a series of cams driven by said drive means and means controlled by said cams and by the sheets delivered to the machine and controlling said clutch whereby said cylinder becomes disconnected from said drive means upon failure of delivery of a sheet to the machine.

7. In a machine of the character described, a rotatable impression cylinder, drive means, a releasable clutch connecting said cylinder with said drive means and releasable at one point only in the rotation of said cylinder through one printing cycle, means for moistening sheets delivered to the machine and feeding them to said cylinder comprising sheet-engaging elements separable to permit of the introduction of the sheets between said elements, a series of cams driven by said drive means and operating to separate said elements, and means controlled by said cams and by the sheets delivered to the machine and controlling said clutch whereby said cylinder becomes disconnected from said drive means upon failure of delivery of a sheet to the machine, and means actuated by said cylinder in its movement responsive to the action of one of said cams for rendering succeeding ones of the cams inoperative to separate said elements.

8. In a machine of the character described, a rotary impression cylinder, means for driving said cylinder, a roller between which and said cylinder the sheets to be printed are passed, a clamp device for clamping a sheet to said cylinder and extending, when in open condition, beyond the periphery of said cylinder and engageable with said roller in the rotation of said cylinder in one direction for moving said device to clamping position, means operative to move said clamp device to open position, and means operating automatically to move said clamp device to clamping position before reaching said roller upon reverse rotation of said cylinder.

9. In a machine of the character described, a rotatable cylinder, drive means therefor, a master sheet receiving and gripping mechanism on said cylinder, a copy sheet feeding mechanism, a copy sheet moistening mechanism, a table for said sheets, and manual control means for said first named mechanism operable to cause release of the old master sheet after passing said sheet feeding mechanism, said first named mechanism being operable to receive and grip a new

master sheet fed to it from said sheet feeding means.

10. A machine for reproducing copies from a master sheet having a record formed thereon in reverse, comprising in combination, a rotatable cylinder, gripping mechanism on said cylinder for seizing and holding one edge of a master sheet thereon, a moistening device adapted to moisten one surface of the copy sheets before they are 5 pressed against the master sheet on said cylinder, means for pressing the moistened copy sheets against the master sheet during a portion of the revolution of the cylinder, a sheet support adjacent said cylinder for copy sheets and new 10 master sheets, means to release the gripping mechanism on a previously gripped master after the gripping mechanism passes the copy sheet engaging position, means for feeding the new master from said support, and means closing the 15 gripping mechanism on said new master after it leaves the support, said releasing and closing means being normally inoperative, and manually controlled means for rendering them operative when it is desired to change the master. 20

11. A machine for reproducing copies from a master sheet having a record formed thereon in reverse, comprising in combination, a rotatable cylinder, gripping mechanism on said cylinder for seizing and holding one edge of a master sheet 25 thereon, a moistening device adapted to moisten one surface of the copy sheets before they are pressed against the master sheet on said cylinder, means for pressing the moistened copy sheets against the master sheet during a portion of the revolution of the cylinder, a sheet support adjacent said cylinder for copy sheets and new master sheets, means to release the gripping mechanism on a previously gripped master after the gripping mechanism passes the copy sheet engaging position, means for feeding the new master from said support, and means including said pressing means 30 for closing the gripping mechanism on said new master after it leaves the support, said releasing and closing means being normally inoperative, and manually controlled means for rendering them operative when it is desired to change the master. 35

12. In a machine of the character described, a rotatable cylinder, drive means therefor, a master sheet receiving and gripping mechanism on said cylinder, a copy sheet feeding mechanism, a copy sheet moistening mechanism, a table for said sheets, and manual control means for said first named mechanism operable to cause release of the old master sheet after passing said sheet feeding mechanism, said first named mechanism being operable to receive and grip a new master sheet fed to it from said sheet feeding means, a pressure roller cooperating with said gripping mechanism to close the gripping mechanism on the new master sheet, and thereafter serving to press the copy sheets against the new master sheet. 40

13. A machine for reproducing copies from a master sheet having a record formed thereon in reverse, comprising in combination, a rotatable

cylinder, gripping mechanism on said cylinder for seizing and holding one edge of a master sheet thereon, a moistening device adapted to moisten one surface of the copy sheets before they are pressed against the master sheet on said cylinder, means for pressing the moistened copy sheets against the master sheet during a portion of the revolution of the cylinder, a sheet support adjacent said cylinder for copy sheets and new master sheets, means to release the gripping mechanism on a previously gripped master after the gripping mechanism passes the copy sheet engaging position, means for feeding the new master from said support, and means closing the gripping mechanism on said new master after it leaves the support, said releasing and closing means being normally inoperative, and manually controlled means for rendering them operative when it is desired to change the master, said device having means to lock the gripping mechanism in closed position upon reverse rotation of the cylinder. 45

14. In a machine of the character described, a frame, an impression cylinder rotatably mounted therein, a platen roller, master sheet clamping means on said cylinder, a guide table for guiding copy sheets fed to said cylinder between the platen roller and said cylinder, drive means for rotating said cylinder, a manually operable lever adapted when actuated to cause opening of said clamping means to release the master sheet at a predetermined point in the rotation of said cylinder, a pair of combined sheet feeding and moistening rollers cooperating with said table and driven by said drive means, means to stop said cylinder with the clamping means registered with said table whereby all copy sheets fed from said table properly register with a master held by said clamping means, a lost motion connection between said drive means and said cylinder, and a direct drive connection between said drive means and said moistening and feeding rollers whereby to advance a sheet from said rollers to said cylinder before starting the cylinder. 50

15. In a machine of the character described, a rotatable cylinder, drive means therefor, a master sheet receiving and gripping mechanism on said cylinder, a copy sheet feeding mechanism, a copy sheet moistening mechanism, a table for said sheets, and manual control means for said first named mechanism operable to cause release of the old master sheet after passing said sheet feeding mechanism, said last named means comprising a lever on said cylinder connected to said gripping mechanism to open and close the same, 55 spring means for holding said lever in gripping mechanism opening or closing position, a movable stop member on the machine, a stop engaging member on said lever, and a manually operable member for moving said stop member into the path of the stop engaging member on the lever. 60
